UNITED STATES PATENT OFFICE.

MIRABEAU SIMS, OF LLANERCH, PENNSYLVANIA.

BALLAST TREATING.

1,329,554.

Specification of Letters Patent.

Patented Feb. 3, 1920.

Application filed June 7, 1916, Serial No. 102,162. Renewed August 13, 1919. Serial No. 317,344.

To all whom it may concern:

Be it known that I, MIRABEAU SIMS, a citizen of the United States, residing at 610 Coopertown street, Llanerch, in the county of Delaware, State of Pennsylvania, have invented a new and useful Ballast Treating, of which the following is a specification.

The invention relates to improvements in ballast treating. The object is to provide improved method and means for removing or translating material such as the ballast, from between railroad ties or adjacent thereto and replacing the same, and means for cleaning the ballast where cleaning is necessary.

It is well known that ballast must be removed from between the ties for the purpose of cleaning the same, or repacking, or for the purpose of replacing worn ties by new ones. It is also common in correcting the grade of the road bed to take material from adjacent land or banks or to deliver material thereto. It is known that the process now universally employed in such removal is extremely slow and tedious; requiring the labor of many men.

The present invention provides method and means for such removal, cleaning and replacing, which accomplish the same amount of work in a much shorter space of time, and by the employment of only two or three men, when, by the now common method, a great many men are required.

Referring to the drawings, which illustrate merely by way of example, suitable means for effecting my invention—

Figure 1 is a plan view of suitable apparatus for effecting my method.

Fig. 2 is a side elevation of same.

Fig. 3 is a front end elevation.

Fig. 4 is a rear end elevation.

Fig. 5 is a plan view on an enlarged scale, of a device for loosening the ballast at the intake mouth of the apparatus.

Fig. 6 is an elevation of same.

Fig. 7 is a section on line 7—7 of Fig. 5.

Similar numerals refer to similar parts throughout the several views.

The floor or platform 10 is mounted on the wheels 11 adapted to track on the rails of the railroad to be operated upon. Upon this platform 10 is mounted the frame 12 upon which is supported the exhaust chamber 13, by means of the trunnions 14. Chamber 13 is connected by the pipe sections 15 and 16 with the exhauster or blower 17,

which draws air from chamber 13 and discharges to atmosphere. Blower 17 is also mounted on the platform 10 and is driven by the engine 18, which is shown as a steam engine mounted on platform 10 and deriving its steam through pipe 19, adapted to be connected with the boiler of the locomotive employed to move the car or platform 10. Connected with the chamber 13, about midway its vertical extension, is the conveyer pipe 20, which is provided with the three branches 21, 22 and 23 leading from intake mouths within the hoods 24, 25 and 26, one between the rails and one on each side thereof; said hoods extending sufficiently beyond the ends of the ties 27 to operate upon the ballast that usually lies around the ends of same. The total cross-sectional area of the three branches is slightly less than the cross-sectional area of the main pipe 20. The several hoods 24, 25 and 26 are vertically movable with respect to the intake ends of pipes 21, 22 and 23, and are supported and moved by cables 28 running on sheaves 29 and operated by the hand lever 30, and held in position by pawl and ratchet 31 and 32. By this means the hoods may be lifted free of switches, cross-rails and the like.

The chamber 13 is provided with the conical bottom 33 discharging to the chute 34 which delivers to the inclined rotating screen 35. The siftings from screen 35 are delivered to the two hoppers 36 and 37, which deliver to the conveyer pipe 38, by the short connecting pipes 39 and 40 which are inclined to said pipe 38. The blower 41 is connected with the engine 42 and forces air into the rear end of pipe 38 serving to carry the siftings through said conveyer pipe 38 to any desired point such as a gondola car not shown.

The screen 35 is rotating by means of the gear or annular rack 43 on the end thereof and a coöperating pinion driven by a belt 44 from the engine 42.

A tub or receptacle 45 is provided at the discharge end of the rotating screen and has a chute 46 projecting therefrom. This tub 45 is preferably mounted on rollers or casters 47, so that the tub may be rotated to bring the chute into different positions, and thus provide means for delivering the screened ballast to any desired point.

In case the ballast becomes unduly packed between the ties, so that it is difficult to move

it by the suction created at the mouths of the conveyer pipes 21, 22 and 23, a device is provided for the intake ends of these conveyer pipes, such as is illustrated in Figs. 5, 6 and 7. It comprises the housing 48 secured to the end of the pipe as for example 21. In this housing is provided an annular channel, in which rotates a collar or other suitable body 49, having a peripheral rack 50, coöoperating with the pinion 51 which is driven by the flexible shaft 52, from any suitable source of power, such for example as the engine 18. This rotating body 49 is provided with a series of fingers or spikes 53 adapted to engage and loosen the ballast or other material to be operated upon as the same is drawn into the conveyer pipes.

This device may also be advantageously used with a suitable suction nozzle in other analogous ways; such for example, where it is desired to remove portions of the banks flanking the railroad, or to translate material from one part of, or from a place adjacent the road bed, to another place, and the device is especially useful when operating upon hard, stony, or clay soil which must first be broken up before removing.

Operation.

30 The method of operation which may be effected by the apparatus above described is as follows:—

The suction hoods 24, 25 and 26 are lowered into position over the ties and between 35 and on each side of the rails as shown in Figs. 1 and 2. The blower 17 then operates to create a suction in chamber 13 which is communicated through the conveyer pipe 10 to the several suction mouths and surrounding hoods 24. This carries the ballast or other material through conveyer pipe 20 and delivers the same into chamber 13, where it falls toward the bottom of the chamber.

A suitable valve 18 having a counterbalance 13^b is provided as shown in Fig. 2, at the discharge in the bottom 33 of chamber 13. This valve is adapted to open and discharge the ballast and dirt or other material, when a predetermined amount of material has collected in chamber 13.

This ballast and dirt is delivered to the rotating screen 35 whereby the dirt is sifted into the hoppers 36 and 37, and carried therefrom by the pipe 38, by the action of 55 the blower 41 to a gondola car, or other suitable place, while the clean ballast is delivered to the tub 45 and thence, through the chute 46, to any desired point as described.

60 It will be understood that the car or platform structure 10 is moved step by step, carrying the suction nozzles from the space

between one pair of ties to the next space and so on, taking out the ballast in front of the apparatus and delivering it to the rear. 65

In case a ballast is used that does not need screening, for example cinder, the screen may be removed, and the ballast delivered directly through chute 34 to the required point, or, in case it is not desired to return 70 the ballast to between the ties again directly, as above described, the screen may be removed or opened at the bottom and the ballast delivered from chute 34 to hopper 36 and carried to any desired point through 75 conveyer pipe 38.

When it is desired to move the structure through a tunnel or under a bridge the pipe sections 15 and 16 may be disconnected, as for example at 54, and from the blower at 80 55, while pipe 20 is disconnected at joint 56. The section 16 is then moved forward, on the supporting rollers 57, into the position shown in the dot and dash lines, and the chamber 13 is tilted on its trunnions in 85 the position also shown in the dot and dash line in Fig. 2. Any suitable means for moving the chamber into the horizontal position and back into the vertical position may be employed. 90

The hoods 24 and 26 may also be elevated and turned on their respective pipe ends into position with their longitudinal extensions parallel with the tracks so that no portion of same will extend beyond the 95 ends of the ties.

What I claim is:—

1. The method which consists in translating railroad ballast from between the ties by pneumatic pressure and depositing the 100 same between other ties, and removing foreign substances therefrom before depositing same.

2. The method which consists in lifting the ballast from between the railroad ties by 105 pneumatic pressure and screening the dirt or other foreign substances therefrom, and depositing the cleaned ballast at required places.

3. The method which consists in lifting 110 the ballast from between the railroad ties and screening the dirt or other foreign substances therefrom, and depositing the cleaned ballast at required places, and conveying by pneumatic pressure the dirt to 115 required places of deposit.

4. Means for translating ballast and intermingled dirt from between ties, by pneumatic pressure, means for screening said material and for depositing the cleaned ballast 120 at required points.

MIRABEAU SIMS.
